(57) **CLAIM**

The ornamental design for a pair of headlight bezels for agricultural product sprayer, as shown and described.

DESCRIPTION

FIG. 1 is an isometric view of a pair of headlight bezels for agricultural sprayer in accordance with the present invention;

FIG. 2 is a close-up isometric view of the headlight bezels of FIG. 1;

FIG. 3 is a side elevation view of a first headlight bezel of FIG. 1;

FIG. 4 is a side elevation view of a second headlight bezel of FIG. 1

FIG. 5 is a front elevation view of the headlight bezels of FIG. 1;

FIG. 6 is a rear elevation view of the headlight bezels of FIG. 1; and,

FIG. 7 is a top plan view of the headlight bezels of FIG. 1. In the drawings, the broken lines depict portions of an agricultural product sprayer that form no part of the claimed design.
